UNITED STATES PATENT OFFICE

2,468,934

PNEUMATIC CLEANING DEVICE

Teunis P. Kleyn, Muskegon, Mich.

Application January 8, 1946, Serial No. 639,833

2 Claims. (Cl. 261—123)

1

This invention relates to cleaning apparatus of the pneumatic type, and more particularly, to a pneumatic cleaning apparatus having a liquid filter element.

A main object of the invention is to provide a novel and improved pneumatic cleaning device which is very simple in construction, easy to operate and readily adaptable for use either as a vacuum cleaner or as a blower.

A further object of the invention is to provide an improved pneumatic cleaning apparatus which is very efficient in operation, said apparatus having a liquid filter device which effectively strains all dirt from the intake air stream produced by the device and delivers clean air from its exhaust passage.

Further objects and advantages of the invention will become apparent from the following description and claims, and from the accompanying drawings, wherein:

Figure 1 is a vertical cross sectional view of a pneumatic cleaning device constructed in accordance with the present invention.

Figure 2 is a horizontal cross sectional view taken on line 2—2 of Figure 1.

Referring to the drawing, 11 designates the main housing for the cleaning device, said housing being circular in horizontal cross section and being more or less pear-shaped in contour, the section of greatest area being located in the lower portion thereof. The top of housing 11 is provided with a removable closure member 12 having a handle 13. The housing is supported on four wheels 14 for readily moving the housing to desired locations.

Positioned in housing 11 is a vertical riser conduit 15 communicating with the outside atmosphere by an intake conduit 16 which passes through the side wall of housing 11 at its bottom portion. Mounted on the bottom wall of housing 11 adjacent intake conduit 16 is an electric motor 17 whose shaft projects into conduit 16 and carries an air impeller fan 18 adapted to create a strong suction effect at the entrance to conduit 16 when the motor is energized. Projecting through the side wall of housing 11 above conduit 16 is a second conduit 19 provided with a flap valve 20 pivotally mounted at the junction between conduit 19 and riser 15, said flap valve 20 being manually controlled by a rotary rod member 21 extending outside of housing 11 substantially at right angles to conduit 19. Normally the flap valve 20 is in its vertical position, as shown in Figure 1, whereby conduit 19 is blocked and the upper portion of riser 15 is in communication with

2

intake conduit 16. Valve 20 may be rotated 90° as indicated by the dotted arrow to a position indicated by the dotted line wherein conduit 19 is in communication with intake conduit 16 and the upper portion of riser 15 is blocked. In this position of valve 20 the apparatus operates as a blower and valve 20 is maintained closed by the air pressure developed below it by fan 18. As such the apparatus may be employed for spraying various materials such as insecticides and the like.

Removably supported in the upper portion of housing 11 is a cylindrical container 22 of light material, such as sheet metal, said container having an upper annular flange 23 which rests on a plurality of radial lugs 24 formed in the upper wall portion of housing 11. Container 22 is provided with a handle 25 for lifting it out of and replacing it inside of housing 11. Positioned inside container 22 is a removable cylindrical sleeve member 26 having a funnel-shaped top wall 27 formed with a depending central spout portion 28. A handle 29 is provided on top wall 27 for lifting or carrying sleeve member 26.

Sleeve member 26 is provided internally thereof with a series of spaced horizontal baffles 30, each portion having a semi-circular screen portion 31. The screen portions 31 of adjacent horizontal baffles 30 are oppositely disposed to provide a tortuous passage for air circulating upwardly through sleeve member 26. The lower portion of container 22 contains water or other suitable fluid for washing dust or dirt out of the air as it circulates upwardly through the sleeve member. A removable conduit 32 which is inverted V-shape connects the top end of riser conduit 15 to the lower internal portion of container 22, the depending portion of conduit 32 passing through suitable vertically aligned openings provided therefor in the horizontal partitions 30. A full screen 31' is provided above the topmost partition 30, a suitable opening for conduit 32 being also provided in said full screen 31'.

Positioned above blower conduit 19 in the side wall of housing 11 at the widest portion thereof is an exhaust conduit 33 through which the filtered air passing through the apparatus leaves housing 11.

When the device is employed as a vacuum cleaner valve 20 is in its normal position as shown in Figure 1. Motor 17 is energized, producing suction at intake conduit 16. Dirt-laden air picked up by a suitable cleaning tool connected to conduit 16 is drawn up through riser 15 and passes through conduit 31 into the lower portion 55 of container 22. The air passes upwardly through

the fluid and the staggered screen portions 31 of the respective horizontal baffles 30 and passes out of sleeve member 26 through depending spout 28, said air having been cleansed by the fluid of all dirt and dust initially carried thereby. The clean air then leaves housing 11 through exhaust conduit 33.

When sleeve member 26 and container 22 require cleaning they may be readily removed, conduit 32 being first disengaged and removed from housing 11 to thereby free sleeve member 26 and container 22 for removal.

While a specific embodiment of a pneumatic cleaning device has been disclosed in the foregoing description, it will be understood that various modifications within the spirit of the invention may occur to those skilled in the art. Therefore it is intended that no limitations be placed on the invention other than as defined by the scope of the appended claims.

What is claimed is:

1. In a portable pneumatic cleaner, the combination, which comprises, a housing having inlet and outlet connections through a wall thereof, a closure for the upper end of the housing, a blower in said housing associated with said inlet connection, an air duct extending from said inlet connection and blower upward to a point adjacent the upper end of the housing, a cylindrical fluid container with a circumferential flange extending outward from the upper end thereof, means removably suspending said fluid container by the flange thereof in said housing with the walls thereof spaced from the walls of the housing, an inverted cylindrical element open at the lower end and substantially closed at the upper end freely positioned in said fluid container with the walls thereof spaced from the walls of the container, said inverted element having an outlet opening in the upper end thereof, a plurality of spaced horizontal baffle elements in said inverted container, said baffle elements comprising solid semi-circular sections and complementary semi-circular sections formed of screen elements, the solid sections and screen elements alternately positioned in said baffles to interrupt direct passage of air therethrough, and an inverted U-shaped air duct with one leg thereof adapted for sliding contact with the air duct extending upward from the inlet connection, and the other leg thereof extending downward through the baffles of said inverted element to a

point in the lower part thereof below the level of a liquid in the liquid container and removable with said inverted element.

2. In a portable pneumatic cleaner, the combination, which comprises, a housing having inlet and outlet connections through a wall thereof, a removable closure for the upper ends of the housing, a blower in said housing associated with said inlet connections, an air duct extending from said inlet connection and blower upward to a point adjacent the upper end of the housing, a cylindrical fluid container with a circumferential flange at the upper end, means removably suspending said fluid container in said housing with the walls thereof spaced from the walls of the housing, an inverted cylindrical element open at the lower end and substantially closed at the upper end freely positioned in said fluid container with the walls thereof spaced from the wall of the container, said inverted element having an outlet opening in the upper end thereof, a plurality of spaced horizontal baffle elements in said inverted container, said baffle elements comprising solid semi-circular sections and complementary semi-circular sections formed of screen elements, the solid sections and screen elements alternately positioned in said baffles to interrupt direct passage of air therethrough, an inverted U-shaped air duct with one leg thereof associated for sliding contact with the air duct extending upward from the inlet connection and the other leg extending downward through the baffles of said inverted element to a point in the lower part thereof below the level of a liquid in the liquid container, said U-shaped duct adapted to be removed with said inverted elements, said housing having an auxiliary outlet connection extending through the wall thereof associated with the said inlet connections, and a valve element adapted to direct air from the blower outward through said auxiliary outlet connection.
